UNITED STATES PATENT OFFICE

2,616,666

COLLAPSIBLE VEHICLE BOOM

Burton Honey, Okanogan, Wash.

Application December 3, 1948, Serial No. 63,365

1 Claim. (Cl. 254—139.1)

1

This invention relates to automotive vehicle and boom assemblies, such as are used by utility companies for erecting line poles and for similar purposes, and more particularly to such an assembly wherein the boom may be raised for use and lowered for transportation and storage.

Utility trucks used in the repair and construction of electric power and telephone and telegraph lines are equipped with boom structures for raising poles, and supporting the poles in upright position until sufficient earth has been tamped around the lower ends of the poles to support them. Such a boom is usually a three legged structure having two upwardly convergent main legs secured at their bottom ends to the rear end of the vehicle frame, and a third leg convergent with the main legs at its upper end and secured at its bottom end to the vehicle frame intermediate the width and forwardly of the rear end of the latter. These three legs support a crown pulley at their upper, convergent ends and a suitable cable is suspended over the crown pulley and wound at one end on a power operated, vehicle carried winch and is used to raise and support line poles and for other purposes.

At present the boom structures are fabricated of separate and separable components and the boom must be completely assembled and attached to the vehicle each time it is erected for use, and disassembled, detached from the vehicle and its component parts stored in the vehicle for storage and transportation. Erecting and dismantling such a boom structure is an extremely laborious and time consuming operation and involves great danger of injury to the workman. The storage of the parts in the vehicle also necessitates keeping the interior of the vehicle clear and precludes the use of this space for other purposes.

It is therefore among the objects of the present invention to provide an improved vehicle and boom assembly wherein the boom is so attached to the vehicle that it can be raised and lowered by the boom cable and power winch and does not have to be assembled for use and dismantled for storage and transportation, and requires little or no manual effort for its erection and retraction, in which the boom is stored on the top of the vehicle leaving the interior space of the vehicle free for other purposes than storage of the boom parts, and which assembly can utilize conventional vehicle, boom, winch and cable components without material modification, and is strong and durable in construction, easy to use, and simple and economical to provide.

2

Other objects and advantages will become apparent from a consideration of the following description and the appended claim in conjunction with the accompanying drawings, wherein:

5 Figure 1 is a side elevation of a vehicle and boom assembly showing the application thereto of boom lowering and raising means illustrative of the invention;

10 Figure 2 is a rear end elevation of the boom and vehicle assembly illustrated in Figure 1;

Figure 3 is a view similar to Figure 1, showing the boom structure in two partly raised or partly lowered positions;

15 Figure 4 is a view similar to Figure 1, showing the boom structure in completely lowered position; and

20 Figure 5 is a transverse cross section on a somewhat enlarged scale taken on the line 5—5 of Figure 1, and showing structural details of the assembly.

With continued reference to the drawings, the vehicle, generally indicated at 10, may be a conventional truck having front wheels 11, rear wheels 12, an engine compartment 13, a driver's cab 14 and a chassis frame 15 extending over and rearwardly of the rear wheels 12. In utility trucks of the character indicated, two elongated tool and equipment boxes 16 are mounted on the frame 15, one at each side of the frame to provide between them an internal space in the front end of which a winch 17 is located. The side boxes 16 extend upwardly from the chassis frame 15 to a level somewhat above the top of the cab 14 of the truck and include respective side frames securely fastened at their bottoms to the truck frame 15. A suitable floor is provided for the space between the side boxes and the winch 17 is mounted in this space on the vehicle floor and is power operated from a power take-off of the vehicle transmission. The winch is controlled for either power or brake operation by suitable manually operated means, such as the hand lever 18. Apertured lugs 19 extend rearwardly from the rear end of the frame 15, or from a suitable tail plate covering the rear cross member of the frame and are arranged in closely spaced pairs with one pair disposed adjacent each end of the rear frame member, and a pair of spaced apertured lugs 20 extend upwardly from the floor of the vehicle substantially midway the width of the space between the side boxes 16 and forwardly of the rear end of the frame.

40 The boom, generally indicated at 21, is a three legged structure having two main legs 22 which are conveniently formed of continuous metal

45

50

55

tubes and a third telescopic leg 23. Each of the main legs 22 has secured to and projecting from its lower end an apertured lug 24 received between a corresponding pair of frame carried lugs 19 and detachably secured to the frame carried lugs by a suitable bolt or pin 25 extending through aligned apertures in the associated lugs 19 and 24. At their upper ends, these main legs 22 are flattened or provided with suitable, solid extensions 26 apertured to receive a bolt or pin 27, which constitutes an axle for a crown pulley 28 rotatably mounted on the upper, convergent end of the boom.

The third leg 23 comprises two telescopically associated tubular members 29 and 30, the larger, 29, of which is provided with a series of longitudinally spaced apart apertures 31 and the smaller, 30, of which is provided near one end with a pair of aligned apertures. A locking pin 32, extendible through the apertures in the smaller tube 30 and through a selected pair of aligned apertures 31 in the larger tube, secures the two telescopically associated tubes 29 and 30 together in a manner to provide a desired length for the third leg 23 of the boom structure. At the lower end, the smaller tube 30 is flattened or provided with a flat, solid extension receivable between the two lugs 20 upstanding from the vehicle floor and apertured to receive a pin or bolt 33 for detachably securing the lower ends of the leg 23 to the lugs 20. At its upper end, the larger tube 29 is provided with a pair of longitudinally extending, aperture plates 34, which receive the crown pulley 28 between them and through which the crown pulley axle 27 passes. By this means, the crown pulley is rotatably mounted at the upper, convergent end of the boom structure and the three legs of the boom are solidly connected together at their upper ends.

A boom cable 35 is wound at one end on the drum 36 of the winch 17 and is suspended over the crown pulley 28 and provided on its free end with a suitable hook 37 or other attaching device.

With the structure so far described, the boom legs, the crown pulley 28 and the mounting pins are carried in the vehicle as separate components and when it is desired to erect the boom for use, these components may be assembled together and mounted on the vehicle in the manner indicated above, and when the use of the boom has been completed, the boom may be completely disassembled and its several parts stored in the vehicle space between the side boxes 16 for transportation or storage. This, as explained above, is a laborious and time consuming operation, involving serious danger of personal injury to the workmen assembling and disassembling the boom, and the present invention contemplates the provision of simple and efficient means for raising and lowering the boom without the necessity of assembling or disassembling the component parts thereof.

In line with the present invention, a first transverse bar or shaft 38 is secured at its opposite ends to the rear ends of the side boxes 16 by suitable clips 39 surrounding the ends of the bar 38 and secured to the rear ends of the side boxes at the upper ends of the latter. A cable guide sheave 40 is journalled on the transverse bar 38 intermediate the length of the latter and at a location slightly displaced from the rearwardly extending plane of the third leg of the boom. A second transverse bar 41 extends between the bottom ends of the two main legs 22 of the boom.

and is secured at its ends to the bottom ends of these main legs by suitable brackets or fittings 42, and a cable guide sheave 43 is journalled on the transverse bar 38, substantially at the mid length location of the latter. A suitable hook or eye 44 is secured to the rear end of the frame 45 in position to lie directly below the cable sheave 43 and projects rearwardly from the rear cross member of the frame to receive the hook 37 of the cable 35.

A respective saddle 45 is secured to each main leg 22 of the boom and extends forwardly from the corresponding main leg in alignment with the first or upper cross bar 38. Each of these saddles may conveniently comprise a triangular bracket 46, projecting outwardly from the boom leg and a U-shaped clip 47 secured to the outer corner of the triangular bracket and having legs spaced apart a distance substantially equal to the diameter of the bar or shaft 38.

Assuming now that the boom is in its erected position, as illustrated in Figures 1 and 2, and that it is desired to lower the boom by use of the power operated winch 17, the pin 33 is first removed to free lower end of the third leg 23. The pin 32 is then removed and the third leg shortened until its bottom end will pass over the transverse bar 38 and when the bottom end of the third leg has been passed over the transverse bar, the upper end of the boom is pulled forwardly until the clips 47 of the saddles 45 receive the bar 38 to pivotally support the boom. The cable 35 is then brought over the sheave 43 and the hook 37 engaged with the eyes 44. The pins or bolts 25, securing the bottom ends of the main legs of the boom to the vehicle frame, are then removed and by using the winch brake to gradually pay out the cable 35, the upper end of the boom is lowered from the position shown in full lines in Figure 3 through the position shown in dotted lines in that figure to the fully lowered position shown in Figure 4. During this lowering of the boom, the boom is held against falling by a force exerted by the cable 35 between the cable sheave 43 and the eye 44 with the transverse bar 38 serving as a fulcrum. When the boom is fully lowered, it rests upon a suitable chock 48 extending transversely across the upper sides of the side boxes 16 near the forward ends of the latter. After the boom has been lowered to the position shown in Figure 4, it may be secured by a suitable latch or tie, if desired.

The tail plate has at its lower edge a rearward extension 49 providing a shelf which will prevent the main legs of the boom from falling when the lower ends of such main legs are detached from the lugs 19.

When it is desired to raise the boom from the position shown in Figure 4 back to the erected position shown in Figures 1 and 2, power is applied to the winch 17 to wind in the cable 35. This winding in of the cable forces the sheave 43 downwardly carrying with it the bottom ends of the main legs of the boom until the lugs 24 are brought into position between corresponding pairs of lugs 19. The pins or bolts 25 are then inserted so that the boom is held in a position approximating the full line position of Figure 3. The hook 37 is then released from the eye 44 and the lower end of the third leg 23 brought out over the bar 38 and secured to the lugs 20 by the pin 33. The upper end of the boom is then forced rearwardly until the desired rearward inclination of the main legs 22 of the boom is obtained whereupon the pin 32 is inserted through the tele-

scopically associated tubes 29 and 30 of the third leg to rigidly secure the boom in operative condition.

The invention may be embodied in other specific forms without departing from the spirit or essential characteristics thereof. The present embodiment is, therefore, to be considered in all respects as illustrative and not restrictive, the scope of the invention being indicated by the appended claim rather than by the foregoing description, and all changes which come within the meaning and range of equivalency of the claim are, therefore, intended to be embraced therein.

What I claim:

In an automotive vehicle and boom assembly including a vehicle frame, side boxes carried by said frame and terminating short of the rear end of said frame, a power operated winch carried by said frame between said side boxes, a three legged boom carried by said frame and including two main legs and a third, adjustable length leg, a crown pulley carried by said boom at the upper end of the latter and a boom cable wound at one end on said winch and suspended over said crown pulley, means for raising and lowering said boom by said power operated winch comprising means detachably connecting the bottom ends of the two main legs of said boom to said frame at the rear end of the latter, means detachably connecting the bottom end of the third leg of said boom to said frame ahead of the rear end of the frame, a first transverse bar secured to said side boxes near the top of the latter to extend across the space between said side boxes adjacent the main legs of said boom and above said vehicle 35

frame, a second transverse bar secured at its ends to said main boom legs near the bottom ends of the latter, cable sheaves journaled one on each of said transverse bars, saddles carried one by each of said main boom legs rotatably engageable with said first transverse bar to pivotally support said boom when the boom legs are detached from said frame for lowering said boom, said saddles being movable away from said first transverse bar when said boom is erected to permit said main boom legs to assume an upwardly and rearwardly inclined position relative to said frame, and an eye secured to the rear end of said frame for attaching of the free end of said cable to said frame with said cable trained over said cable sheaves, whereby said winch controls the turning of said boom about said first transverse bar as a fulcrum between its erected position and a lowered position in which it rests upon the top of said side boxes.
